GAS MOTOR ENGINE.

No. 408,137.

Patented July 30, 1889.

UNITED STATES PATENT OFFICE.

JOHN J. PURNELL, OF LAMBETH, COUNTY OF SURREY, ENGLAND.

GAS-MOTOR ENGINE.

SPECIFICATION forming part of Letters Patent No. 408,137, dated July 30, 1889.

Application filed May 15, 1889. Serial No. 310,860. (No model.) Patented in England July 12, 1888, No. 10,165.

To all whom it may concern:

Be it known that I, JOHN JAMES PURNELL, a citizen of England, residing at Atlas Works, Webber Street, Lambeth, in the county of 5 Surrey, England, have invented a new and Improved Gas-Motor Engine, (for which I obtained Letters Patent in Great Britain, dated July 12, 1888, No. 10,165,) of which the following is a specification.

10 My invention relates to a gas-motor engine of simple and inexpensive construction, as I describe, referring to the accompanying drawings.

Figure 1 is a front elevation with the valve-case shown in section, and Fig. 2 is a side elevation of a gas-motor engine according to my invention.

On a hollow base A stands a vertical cylinder B, which is open at the top and is surrounded, as usual, with a water-casing. The cylinder has a trunk-piston C, connected to the crank on the fly-wheel shaft D, which is mounted in bearings carried overhead in brackets E, extending up from and in one 25 piece with the cylinder B. In the cavity of the base A is a valve-case containing two valves F and G, both opening upward to a space H in free communication with the interior of the cylinder B. The one valve F is 30 kept closed by a spring f and is opened to discharge exhaust by an arm K of a rocking shaft L, which has another arm M, connected to a crank N, or it might be an eccentric or cam on a counter-shaft driven by gearing O 35 from the shaft D at half the speed. The other valve G is self-acting, opening to admit air by the pipe g, and it has a hollow seating the annular cavity of which is connected to a gas-supply pipe and has numerous 40 small perforations opening to the face of the valve-seating. From the space H a passage leads to a vertical pipe P, which is kept heated by a gas-burner, and which has a cap p, that can be screwed more or less down, so as to diminish or increase the interior capacity of the 45 pipe P.

The action of the engine is as follows: As the piston C ascends, the valve G rises, admitting air mixed with gas into the space 50 below the piston, the valve F at this time remaining closed. The piston then descending compresses the gaseous mixture, and when the pressure is sufficient a portion of the

mixture forced into the heated pipe P becomes ignited. The ignition is communicated 55 to the charge in the cylinder and the piston C is propelled upward. During the subsequent descent of the piston the exhaust-valve F is opened and the products of combustion are expelled. By adjusting the cap p of the 60 heated pipe P, which after each ignition remains charged with products of combustion, the volume of the products contained in the pipe can be so regulated that their compression to the extent necessary to secure ignition 65 of the cylinder-charge takes place just as the piston C reaches the end of its compressing-stroke, thus dispensing with valve-gear such as is usually employed to put the igniting apparatus in communication with the charge. 70

Obviously, instead of employing a cap p, screwing onto the exterior of the heated pipe P, a plunger might be screwed into its interior in order to regulate its capacity for the purpose above stated. 75

Having thus described the nature of my invention and the best means I know of carrying the same into practical effect, I claim—

A gas-motor engine having a vertical cylinder made with brackets projecting up therefrom to carry the crank-shaft, and having in a hollow base under the cylinder a valve-box containing a self-acting air and gas supply valve and an exhaust-valve closed by a spring and opened at every alternate revolution of 80 the crank-shaft by a lever worked by a crank eccentric or cam caused to revolve by gear at half the speed of the shaft, having also in communication with the cylinder-bottom an igniting-pipe heated by a burner, this pipe 85 being adjustable in length, all substantially as described.

In testimony whereof I have signed my name to this specification, in the presence of two subscribing witnesses, this 3d day of May, 95 A. D. 1889.

J. J. PURNELL.
